UNITED STATES PATENT OFFICE.

MAX KLEIN, OF NEW YORK, N. Y., ASSIGNOR TO SHAPIRO & ARONSON, INC., A CORPORATION OF NEW YORK.

DESIGN FOR A LIGHTING FIXTURE.

Application filed November 17, 1923. Serial No. 7,796. Term of patent 7 years.

To all whom it may concern:

Be it known that I, MAX KLEIN, a citizen of the United States, residing at New York, in the county of New York and State of New York, have invented a new, original, and ornamental Design for Lighting Fixtures, of which the following is a specification, reference being had to the accompanying drawing, forming part thereof.

Fig. 1 is a side view of a lighting fixture showing my new design.

Fig. 2 is a bottom view of the body portion of the fixture. Only a fragmentary portion of the design is shown inasmuch as it is duplicated on the other half of the body portion. The lamp bulbs are omitted from this view for the sake of a clear showing of the design.

I claim:

The ornamental design for a lighting fixture, as shown.

MAX KLEIN.
